FIG. 1

FIG 2

FIG 3

Fig. 1 is a perspective view of a handbag showing my new design.

Fig. 2 is a front elevational view of the handbag shown in Fig. 1.

Fig. 3 is a bottom plan view of the handbag shown in Fig. 1.

Applicant's handbag is characterized by the heavy undulating knitted area in the intermediate body portion, contrasted with the straight line ribbed knitting in the end portions of the handbag, and by the combination of drawstrings and double hoop handles, the hoops being held in a loop-type fringe which extends substantially one-third down the side of the handbag.

I claim:

The ornamental design for handbag, substantially as shown and described.
